[57] CLAIM

The ornamental design for an ice creeper, substantially as shown and described.

DESCRIPTION

FIG. 1 is a perspective view of an ice creeper showing my new design;

FIG. 2 is an enlarged top plan view of the ice creeper, the straps shown broken away for ease of illustration.

FIG. 3 is an enlarged bottom plan view thereof;

FIG. 4 is an enlarged side elevational view thereof;

FIG. 5 is an enlarged rear elevational view thereof;

FIG. 6 is an enlarged front elevational view thereof. The broken line showing of a shoe or boot in FIG. 1 is for illustrative purposes only and forms no part of the claimed design.
